[57] CLAIM

The ornamental design for a blister package, as shown and described.

DESCRIPTION

FIG. 1 is a front elevational view of a blister package showing our new design;

FIG. 2 is a rear elevational view thereof;

FIG. 3 is a top plan view thereof;

FIG. 4 is a right side elevational view thereof, the left side elevational view being a mirror image thereof; and, FIG. 5 is a perspective view thereof.

*FIG. 1**FIG. 2**FIG. 3**FIG. 4**FIG. 5*
